(57) **CLAIM**

The ornamental design for a genetic analyzer, as shown and described.

DESCRIPTION

FIG. 1 is a top, front, left perspective view of a first embodiment of a genetic analyzer, showing our new design; FIG. 2 is a bottom, rear, left perspective view thereof; FIG. 3 is an enlarged view of detail “3” identified in FIG. 1, for clarity of disclosure;

FIG. 4 is an enlarged view of detail “4” identified in FIG. 2, for clarity of disclosure;

FIG. 5 is a front elevation of the genetic analyzer of FIG. 1; FIG. 6 is a rear elevation thereof;

FIG. 7 is a right side elevation view thereof;

FIG. 8 is a left side elevation view thereof;

FIG. 9 is a top plan view thereof; and,

FIG. 10 is a bottom plan view thereof.

In the drawings, the equal-length broken lines on the genetic analyzer depict unclaimed elements thereof, and form no part of the claimed design.
